UNITED STATES PATENT OFFICE.

ISRAEL BORKIN, OF NEW YORK, N. Y.

DEVICE FOR SUPPORTING AND ADJUSTING MATRIX-BANDS.

1,359,665.

Specification of Letters Patent.

Patented Nov. 23, 1920.

Application filed March 28, 1919. Serial No. 285,867.

To all whom it may concern:

Be it known that I, ISRAEL BORKIN, a citizen of the United States, residing at New York, in the county of New York, and 5 State of New York, have invented certain new and useful Improvements in Devices for Supporting and Adjusting Matrix-Bands, of which the following is a specification.

10 This invention relates to devices for supporting and adjusting matrix bands and the objects of the invention are to provide simple and effective means for this purpose, which can be readily adjusted and which 15 can be made relatively inexpensively.

These objects I have accomplished by constructing a holder for the matrix band embodying an elongated support including two relatively slidable parts, a loop at one 20 end of one of the parts, for receiving parts of the band intermediate its bight and free ends, and a keeper on the other part, for receiving the free ends of the band; and also by constructing the holder so that it embodies, similarly to the holder of my application Serial No. 223,294, of which this application is a continuation in part, a tubular stock or handle carrying the keeper, a 25 tightening rod slidably engaged in the tubular stock and carrying the loop, and means for adjusting said band-tightening 30 rod.

Other features and the details of construction will be made clear as the specification proceeds, attention being now invited 35 to the accompanying drawing, wherein I have illustrated the invention embodied in a practical commercial form.

In said drawing, Figure 1 is a top plan view of the device with the matrix band not 40 yet engaged about a tooth; Fig. 2 is a side elevation; Fig. 3 is a view similar to Fig. 2, but showing the band engaged about a tooth; and Fig. 4 is a fragmentary view showing a 45 part of the device in bottom plan.

The elongated support includes the two relatively slidable parts 5 and 12. The numeral 5 designates the stock or handle of the device which is of tubular construction, 50 internally screw-threaded at one end at 6, and provided on one side, near its opposite end with a keeper or holder for one end of the matrix band 7. This keeper is here provided by an arch or spaced ring 8, formed 55 on one side of the stock, in which is mounted a clamp screw 9, for clamping the

doubled end of the band in the passage provided beneath such ring. This passage lies close to the body of the stock and is disposed substantially longitudinally thereof 60 so that the ends of the band lie flat against the stock, and do not protrude or stand out. A firm grip on the band is assured by cupping the bottom of the passage beneath the point of the clamping screw as indicated at 65 11, and by the location of this depression intermediate the ends of the passage the deflection of the band will be localized and thus the band will not be bent to such an extent as to cause the end of the band, if it 70 extends beyond the keeper, from standing out at an angle from the stock.

The band-tightening member comprises a rod 12, the shank of which is slidably engaged in the bore of the stock and which 75 carries a head 13, formed with a slotted opening 14 through which the bight of the band is passed. This rod is held against turning in the stock by a sliding pin-and-slot connection therewith, comprising an 80 outstanding pin or lug 15 on the rod working in a longitudinal slot 16 in the stock. This pin-and-slot connection may also be utilized to limit the longitudinal shifting movement of the band-tightening member. 85

The adjusting means for the band-tightening member consists, in the present disclosure, of a screw rod 17 engaged in the threaded end of the stock, having an exposed finger hold or operating head 18 and 90 projecting into the bore far enough to bear upon the rear end of the rod 12.

It will be apparent that by simply turning the finger hold 18 the matrix band may 95 be tightened or loosened, as desired. The adjustable keeper permits the band to be readily lengthened or shortened for making larger or smaller loops, as required and when adjusted to the proper length the band is securely held. Constructed as described, 100 the movable elements of the device are for the most part housed within the tubular stock and there are no exposed projecting parts liable to cause injury in the use of the device.

The head 13 also preferably carries a 105 cross-piece 19 spaced away from the head, and which may be formed as a loop as indicated. Such loop 19 has a lip 20 overhanging the slotted opening 14. This arrangement facilitates quick mounting and 110 remounting of a matrix band, without dan-

ger of bending sharply or otherwise injuring the same in advancing the free ends of the band beyond the opening 14 and toward and into the keeper 8.

5 The head 13, further, is preferably made convex as indicated at 21 in Fig. 1, that is, across the head and between the feet of the side-legs of slotted opening 14; as I have discovered that by such a construction the 10 life of a band is much increased and cracking of the band is delayed at the points where it changes direction across its flat between opening 14 and keeper 8.

I claim:

15 1. A device of the character described, a matrix band, a tubular stock provided with a longitudinally arranged keeper for the matrix band in one side thereof and extending longitudinally of the stock, means for 20 securing the band in said keeper, a band-tightening rod slidably engaged in the stock and provided at one end thereof with a transverse opening for receiving the band and means for shifting the rod in the tubular stock.

25 2. In a device of the character described, a tubular stock having a depression in one side thereof and a keeper overlying said depression, a matrix band engaged beneath the keeper, a clamp screw adjustably engaged in said keeper above the depression for clamping the band therein, a band-tightening rod slidably engaged in the tubular stock and having an opening therethrough 30 for receiving the matrix band and means for shifting the rod longitudinally of the stock.

35 3. In a device of the character described, a tubular stock screw-threaded at one end and 40 having a keeper on one side thereof near the opposite end, an operating screw engaged with the screw-threaded portion of the stock and extending into the bore of the stock, a band-tightening rod having a shank portion 45 disposed in the bore and engaged by the end of the operating screw and an outer headed portion provided with a transverse

slot to receive a matrix band, a matrix band 50 engaged in said slot and in the keeper loop aforesaid, and means for securing the band in the keeper, the last-mentioned means including a depression in the stock below the keeper and a tightening screw threaded through the keeper and spirally adjustable toward the depression.

55 4. In a device of the character described, an elongated support including two relatively slideable parts, a transverse opening at one end of one of the parts, a matrix band adapted to be bowed and to have its 60 free ends passed through the transverse opening, a keeper for receiving said free ends of the band on the other part near the end thereof adjacent to the band carrying end of the first part, and a second opening 65 on the first part, between the first opening and the keeper, and through which the free ends of the band are guided and pass for entering the keeper.

70 5. In a device of the character described, an elongated support including two relatively slideable parts, one of said parts having a transverse opening adjacent one end thereof, a matrix band adapted to be bowed and to have its free ends passed through 75 the transverse opening, a keeper for receiving said free ends of the band on the other part near the end thereof adjacent to the band carrying end of the first part, and a cross-piece spaced from and carried by the 80 first part between the transverse opening and the keeper, and under which the free ends of the band are guided and pass for entering the keeper.

85 6. The device defined in claim 5, wherein said cross-piece overlaps but lies above the transverse opening.

7. The device defined in claim 4, wherein said second opening is arranged at an angle to the first opening and is provided at its 90 bight with a lip overhanging the first opening.

In testimony whereof I affix my signature.
ISRAEL BORKIN.
